UNITED STATES PATENT OFFICE

149,786

DESIGN FOR A TRAILER

Fred J. Arisman, Salem, Oreg.

Application December 10, 1945, Serial No. 124,564

Term of patent 14 years

(Cl. D14—3)

To all whom it may concern:

Be it known that I, Fred J. Arisman, a citizen of the United States of America, residing at Salem, in the county of Marion and State of Oregon, have invented a new, original, and ornamental Design for a Trailer, of which the following is a specification, reference being had to the accompanying drawings, forming a part thereof.

In the drawings:

Figure 1 is a perspective view of a trailer embodying my new design.

Figure 2 is a fragmentary perspective view from the front of the same with the doors open.

Figure 3 is a top plan view of the same with the drawbars broken away.

Figure 4 is a rear end elevational view of the trailer.

I claim:

The ornamental design for a trailer, as shown.
FRED J. ARISMAN.
